UNITED STATES PATENT OFFICE.

CHARLES T. CHILDERS, OF GALESBURG, ILLINOIS.

DESIGN FOR A FOUNTAIN DISPLAY-STAND.

SPECIFICATION forming part of Design No. 35,012, dated August 27, 1901.

Application filed July 24, 1901. Serial No. 69,585. Term of patent 7 years.

To all whom it may concern:

Be it known that I, CHARLES T. CHILDERS, a citizen of the United States, residing at Galesburg, in the county of Knox and State of Illinois, have invented and produced a new and original Design for a Fountain Display-Stand, of which the following is a specification.

This invention relates to a new and original design for a fountain display-stand; and it has for its object to provide a design of this character which shall be both useful and ornamental.

The leading feature of the design resides in a circular supporting-base, a central stand arising from said base, a plurality of circular horizontal foraminous shelves arranged in spaced relation around the standard, said shelves being successively smaller in diameter from the lowermost to the uppermost shelf and also concentrically related and disposed in the same vertical plane inside of the vertical plane of the supporting-base, and an open spray-cage located at the top of the standard and above the uppermost shelf and having horizontally-disposed disks and a plurality of vertically-disposed rods connecting the latter.

A minor feature of the design resides in the stand having a conical shield arranged at the top of the standard between the spray-cage and the uppermost foraminous shelf.

Other minor features of the design are the circular supporting-base having a peripheral upstanding flange, the circular foraminous shelves having upstanding peripheral foraminous rim portions, and a plurality of downwardly-convergent braces or brace-rods extending from the bottom of the shelves to the said standard.

In the drawings, Figure 1 is a perspective view of a fountain display-stand embodying the herein-described design. Fig. 2 is a top plan view thereof.

Referring particularly to the drawings, the numeral 1 designates the bottom circular supporting-base, provided with a circular pendent rim 2 and a peripheral upstanding flange 3 at the top edge thereof. Arising centrally from the said circular supporting-base 1 is the central tapering standard 4, upon which are arranged a series of circular horizontal foraminous shelves 5. These circular foraminous shelves 5 are arranged one above the other in equally-spaced relation, and each is provided with an upstanding peripheral foraminous rim portion 6. The several shelves 5 are successively smaller in size or diameter from the lowermost to the uppermost shelf, and the same are also concentrically located and disposed in the same vertical plane inside of the vertical plane of the supporting-base 1.

The design also includes a plurality of downwardly-convergent braces or brace-rods 7, extending from the bottoms of the shelves to the standard 4.

Another feature of the design resides in the stand having an open spray-cage 8 located at the top of the standard and provided with horizontal spaced terminal disks 9 and a plurality of vertically-disposed rods 10, interposed between and connecting said disks. Below the said open cage 8, which may be said to be located at the crest of the stand, there is arranged a conical deflector-shield 11, which shield flares downwardly toward the uppermost and smaller foraminous shelf 5.

Having thus described the invention, what is claimed is—

The design for a fountain display-stand herein shown and described.

In testimony whereof I affix my signature in presence of two witnesses.

CHAS. T. CHILDERS.
